UNITED STATES PATENT OFFICE.

ARMIN DEMUTH, OF NEW YORK, N. Y.

AEROPLANE.

Application filed January 2, 1925. Serial No. 12.

My invention relates to aeroplanes, and is intended to provide a construction that will be suitable for carrying considerable weight at great speed, for long distances, and which 5 will exhibit great stability and take up a comparatively small space, especially as regards width.

For this purpose, I have provided a plurality of wings arranged at different levels 10 and at different distances from the nose or bow and stern of the aeroplane, and have also devised a novel arrangement of propellers and their motors or driving mechanism. The invention and its advantages 15 will now be fully described, and the novel features pointed out in the appended claims.

Reference is to be had to the accompanying drawings, illustrating, as an example, an aeroplane embodying my present improvements, Fig. 1 being a plan view of the aeroplane, Fig. 2 a front or bow elevation thereof, and Fig. 3 a side elevation, while Figs. 4 and 5 are vertical sections on lines 4—4 and 5—5 of Figs. 1 and 2 respectively; and Fig. 6 is a diagram of the electric circuits controlling the motors.

The body or fuselage 10 of the aeroplane is of any suitable construction, with provision for the accommodation of crew and 20 passengers as well as freight. At 11 I have indicated portholes for observation and other purposes. Slightly forward of the middle portion of the body 10, two longitudinal hollow stays 12 rise from such body at its 25 outer edges, and the upper ends of these stays are connected with the central wing 13 which extends clear across. In addition thereto, I provide two transversely-aligning forward wings 14, and two transversely-aligning rear wings 15, extending outwardly 30 from the upper portion of the body 10. These wings 14, 15 are therefore at a lower level than the central wing 13. The latter is of considerably greater length or spread 35 than either the forward or the rear wings, these being of substantially equal spread. The length of the body 10 is materially greater than the spread of the central wing 13, and by this construction, in conjunction 40 with the provision of a plurality of wings or supporting surfaces at different levels, I am enabled to reduce the wing spread considerably.

The wings 13, 14, 15 are hollow, and contain the six motors 16 for driving the pro-

pellers 17, 18, 19 arranged at the front edges of said wings, in pairs.

The shafts of the front propellers 17 are preferably in line with those of the rear propellers 19, but the propellers 18 of the central wing 13 are farther apart than those of the front pair 17 or the rear pair 19. It will be understood that the two propellers of the same pair are at the same distance from the longitudinal center of the aeroplane.

Another pair of propellers, 20, is located at the front edge of the central wing 13, but closer together than the front propellers 17 and rear propellers 19. These propellers 20 are driven by motors 16^a located within the hollow stays 12, and the latter are large enough to admit members of the crew, and also to contain accessories such as storage tanks for the gasoline used in the motors. The hollow stays may be provided with port-holes 11^a. Fig. 1 shows that these stays are formed more or less like torpedoes, this stream-line shape reducing resistance. I prefer to make the motors 16^a much more 50 powerful than the motors 16; for instance, each motor 16 might be of 450 horsepower, and each of the motors 16^a from 800 to 1000 horsepower. The propellers 20 and their motors 16^a are at a level slightly below that of the propellers 18 and their motors.

The motors 16^a located within the stays 12 are readily accessible from opposite sides of the body 10 through suitable doors or 55 passages (not shown). The motors 16 and 16^a are readily controlled from a central point in or on the body 10, where I should also locate the controls for the horizontal rudder 21 and the vertical rudder 22 as well as for the ailerons or movable wing-tips 23, 24 located at the ends of the central wing 13 and rear wings 15 respectively. No ailerons are shown on the front wings 14.

The central wing 13 constitutes the main supporting surface of the aeroplane, and the other wings act as auxiliary or stabilizing surfaces. At the front surface formed by the wings 14 lies below the level of the central wing 13, the latter will receive the air currents from the front wings. The rear surface formed by the wings 15 will by its motors and propellers secure a uniform rearward distribution of the other air currents or whirls. A very high degree of stability 110 is thus obtained.

- The pair of extra powerful motors 16^a and their propellers 20 will be amply sufficient to propel the aeroplane. In fact, the pair of propellers 17 will suffice for such propulsion, although at a lower speed, or I might use the propellers 18 alone, or the propellers 19 alone. The speed and power may be increased by putting two or more pairs of propellers in operation at the same time. By having the two motors 16^a of much greater power than the motors 16, I am able to hold the six motors 16 and their propellers idle or in reserve, without reducing the speed very much from the full speed obtained with all eight propellers running.
- A suitable arrangement for enabling the motors to be started (or stopped) either single or in pairs, is illustrated diagrammatically by Fig. 6. At 21 I have indicated the storage batteries or other sources of electricity for the electric ignition systems of the two motors 16^a, and at 21' the batteries for the six motors 16, the eight motors being indicated in substantially the same relation as the one that Fig. 1 indicates for the respective propellers. A wire 22 connects one pole of the battery 21 with one terminal of the electric ignition system of the motor 16^a, and from the other pole of this battery a wire 23 leads to one terminal 24 or 25 of a single-throw, double-pole switch 26. The movable switch members connected with the terminals 24, 25 respectively are adapted to engage contacts 27, 28 respectively connected by wires 29 with the other terminals of the respective ignition systems. It will be evident that with the switch in the "on" position illustrated, the ignition systems of both motors 16^a will be in circuit, so that both motors of this pair will be operated, with the corresponding propellers 20. In order to enable the operator to start only one motor of the pair or to stop either one or both motors of the pair, I have provided two additional switches 30, 31, which are of the single-pole type, and movable independently of each other and of the switch 26. These switches 30, 31 are permanently connected with the respective wires 23, and are adapted for engagement with contacts 32, 33 respectively, permanently connected with the respective wires 29. It will be evident that when the switches 30, 31 are open as shown, and assuming the switch 26 also to be in the open or "off" position, the circuits of the ignition systems of both motors 16^a will be interrupted. If then the switch 30 is brought against the contact 32, this will throw in the ignition of only the left hand motor 16^a; a similar operation of the switch 31 alone, will throw in this ignition of only the right hand motor 16^a. If both motors are to be operated simultaneously, the switch 26 will be used.

Ignition controlling mechanism of the

same character as has been just described in connection with the pair of motors 16^a, is also provided in connection with the three pairs of motors 16, as will be obvious from an inspection of Fig. 6 in which reference numerals with indices, are employed to designate the corresponding parts connected with the motors 16.

I desire it to be understood that mechanism of the same character as shown in the diagram Fig. 6, may be employed to control the electric starting motors for the individual internal combustion engines 16 and 16^a. That is, the aeroplane might have one set of switch mechanism for controlling the ignition systems after the fashion explained in connection with Fig. 6, and another set of exactly the same character for controlling the several electric starting motors of the respective engines. The illustration Fig. 6 will do for the both sets of mechanisms, according as we assume to the wires 22, 29 and 22', 29' to be connected with the ignition systems or with the electric starters. In the latter case, springs or other devices of well-known character would preferably be employed to keep the switches 26, 30 and 31 normally in the open position and to return them to such position when they are released, so that the respective starter circuits would be interrupted automatically as soon as the switches are released.

Various modifications may be made without departing from the nature of my invention as set forth in the appended claims.

It will be understood that the term "aeroplane" as used herein is to be given a broad interpretation, so as to include hydro-aeroplane or so-called flying boats, etc.

I claim:

1. An aeroplane having front, rear, and intermediate wings, and pairs of propellers on said wings, the intermediate wing having a greater number of such pairs than the other wings.
2. An aeroplane having a body, hollow stays rising from said body, a hollow wing connected with the upper ends of said stays, motors within said wing, outer propellers driven by said motors, other motors located within the stays, and inner propellers driven by said other motors and located at a lower level than said outer propellers.
3. An aeroplane having a body, hollow stays rising from said body, a wing connected with the upper ends of said stays, motors within said stays, inner propellers driven by said motors, and located adjacent to the front edge of said wing, outer propellers likewise located adjacent to such front edge, and means for driving said outer propellers.
4. An aeroplane having a body, hollow stays rising from said body, a wing connected with the upper ends of said stays,

motors within said stays, inner propellers driven by said motors and located adjacent to the front edge of said wing, outer propellers likewise located adjacent to such front edge, but at a higher level than the inner propellers, and means for driving said outer propellers.

5. An aeroplane having a plurality of propelling mechanisms arranged in pairs and internal combustion engines for actuating said mechanisms in combination with individual switches each controlling the ignition system of one engine, and main switches each controlling the ignition systems of both engines of the same pairs.

6. An aeroplane having a plurality of propelling mechanisms arranged in groups and internal combustion engines for actuating said mechanisms in combination with individual switches each controlling the ignition system of one engine, and main switches each controlling the ignition systems of all engines of the same group.

7. An aeroplane having a plurality of propelling mechanisms arranged in pairs and internal combustion engines for actuating said mechanisms, in combination with individual electric starters for said engines, individual switches each controlling the starter of one engine, and main switches each controlling both starters of the same pair of engines.

8. An aeroplane having a plurality of propelling mechanisms arranged in groups and internal combustion engines for actuating said mechanisms, in combination with individual electric starters for said engines, individual switches each controlling the starter of one engine, and main switches each controlling all the starters of the same group of engines.

9. An aeroplane having front, rear, and intermediate wings, the intermediate wing being above the front and rear wings, and a pair of propellers on each of said wings.

ARMIN DEMUTH.
